LOUD SPEAKER

Chakir Midhat, Berlin-Eichkamp, Germany

Application June 13, 1931, Serial No. 544,057, and
in Germany June 24, 1930

10 Claims. (Cl. 181—31)

This invention relates to further improvement of loudspeakers of the type described in my United States patent applications Serial Number 321,256, filed November 22, 1928, issued as Patent #1,829,909, dated November 3, 1931, and Serial Number 442,430, filed April 7, 1930, issued as Patent #1,829,910, dated November 3, 1931, in which, besides a larger-surface diaphragm, also a plurality of strings extending under tension over a resonance body, is caused to oscillate. The present improvements relate to the construction of the resonance body, the form of tensioning of the strings, and also the coupling of the strings with the driving unit, as is all fully described hereinafter.

In my above-mentioned application Serial Number 442,430 I have shown a constructional form of the loudspeaker in which the resonance box surrounds the rim of the diaphragm like a baffle board, both faces of the diaphragm remaining free. All parts of the resonance body which are made of wood particularly suited for resonance purposes, are, in that constructional form, united with one another by glueing in the manner known with ordinary stringed instruments so as to constitute a unit.

This manner of composing the resonance body, although practically valuable, suffers nevertheless from the drawback that too much of the expensive resonance wood is used. This drawback is detrimental for the reason that as, in order to attain the desired effect, viz. an increase or strengthening of the resonance in the deeper tone ranges, this effect will be the better attained, the larger the resonance body is.

With my present improved construction of the loudspeaker in question, the just mentioned drawback has been done away with by making only the front wall of good resonance wood, and by connecting this front wall with the other part of the resonance box that is made of a cheap material and is rigid in itself in such a manner that its capability to oscillate is not in the least impaired. Designing the resonance box in this manner presents two more important advantages, in that, in the first place, the manufacture of the loudspeaker is rendered cheaper owing not only to the cheaper material used for a large part thereof but also through economy in work, as only the front wall which is the resonance wall proper need be manufactured after the approved principles followed in the building of stringed instruments, whereas the entire other part of the box can be manufactured in joinery manner; in the second place, a resonance body

designed in this way can be employed also for the housing of the receiving or amplifying apparatus, which is impossible with resonance bodies made according to my application Serial Number 442,430 as in this latter case the parts 60 constituting the box are so united with one another by glueing that the interior thereof is not accessible.

In the constructional forms of the loudspeaker as shown and described in said two former applications all strings are connected with one another at one end by a member specially provided for this purpose. This arrangement suffers, however, from the following drawbacks: firstly, stretching the strings and tuning them 70 to the desired pitch is circumstantial and requires much time, because the stretching or tightening on any one of the strings exerts a certain effect also upon the other strings, that is to say, affects the tuning thereof. Secondly, the 75 comparatively great weight of the member connecting the strips with one another, as stated, is of unfavorable influence. As this member is subjected to the tensile stress of all strings, it must consist of a very solid and, therefore, heavy metal, such as iron, brass or the like. Besides, the weight of said connecting member and the weight of the fastening knots of the 80 strings join one another to constitute detrimental dead weight.

With my present improved loudspeaker the drawbacks mentioned in the preceding lines are obviated by another manner of stretching and fastening the strings, in that, which is the chief feature of this improvement, both ends of each string are affixed to the resonance body, whereas a suitable portion of their middle parts is coupled with the driving unit by means of a clamping device specially designed for this purpose. 90 This permits stretching each string independently of all other strings so that also the tuning of any one of the strings does not affect the pitch of the other strings, and furthermore, the clamping member or device is completely relieved from the tension of the strings so that it can consist of a material of low weight, for instance wood, hard rubber or the like.

As has already been described in my application Serial Number 442,430, it is, with loudspeakers having strings, suited to the purpose to couple only the diaphragm rigidly with the driving unit, whereas the oscillations are transmitted to the strings in a weakened state. This is, according to the above referred to application 110

effected in this way that the member connecting the strings with one another leans against the moving part of the driving unit with a slight elastic pressure. A presupposition for this manner of transmitting the oscillations is this that the moving part of the driving unit is elastically suspended, as is the case with electromagnetic driving units, and that being so, said manner of transmitting the oscillations is not applicable where an electrodynamic driving unit of the usual design is employed. On the other hand, the rigid coupling of the strings with the electrodynamic driving unit is not suited because, owing to the large amplitudes of the oscillatory coil of the driving unit, the oscillations of the strings become too strong whereby the impression is caused that the reproduction contains too many harmonics. In view of that drawback I employ, when using a driving device with large oscillatory amplitude, another form of the transmission of the oscillations, the arrangement and combination being such that, although there is a coupling between the driving device and the strings, still, this is not, as hitherto, a rigid coupling, but is more or less elastically yieldable so that the oscillations are transmitted to the strings only in an enfeebled state.

The invention is illustrated diagrammatically and by way of examples on the accompanying drawings, on which Figure 1 is a front-view of a loudspeaker designed according to this invention, a portion on the left hand side of the figure being removed for want of space, that portion being just such a one as the corresponding portion on the righthand side of the same figure. Figure 2 is chiefly a vertical section in the plane II-II of Fig. 1, only the uppermost part of the figure being shown in side-view. Figure 3 is a perspective view of the middle portions of two sets of strings which cross one another, together with the connecting members for said strings, or sets of strings, this figure being drawn to an enlarged scale relatively to Figs. 1 and 2. Figure 4 is an enlarged view of the parts visible in the middle portion of Fig. 2, the figure showing the coupling of the strings with the moving member of the driving device. And Figures 5 and 6 show a simplified constructional form of the loudspeaker in front-view and in section, all as fully described hereinafter.

In Figs. 1 and 2, 2 denotes the front wall which is designed as a resonance board and consists of a kind of wood having an appropriately good resonance. The transverse ledges 6 glued to said front wall 2 serve in known manner as reinforcement of the same. 3 denotes the rear wall which is designed as a rigid baffle board and may be made of any ordinary wood or of any other cheap material suited for the purpose and as also otherwise used for making ordinary baffle boards.

The resonance board 2 is affixed to the rigid part of the box preferably in such a manner that it can oscillate freely and without any impediment, without transmitting a part worth mentioning of its oscillatory energy mechanically to the rigid part. An example for such a fastening is illustrated in Fig. 2. To the tapering rims of the resonance board are glued ledges 7 which consist of resonance wood and by means of which the resonance board is secured to said rigid part at a few points by means of screws or the like. The ledges 7 form at the same time a part of the side walls of the box. Whereas

the other part 5 is rigid and is firmly connected with the rear wall of the box.

That part of the rigid rear wall which carries the driving device is inserted as a separate part and extends forwardly so much that its foremost portion is located practically in the immediate neighbourhood of the resonance wall at the front of the box. This separate part 3^a is shaped like a truncated pyramid or cone and it need not indispensably be made of wood, but may be made also of a suitable metal, as is indicated in Fig. 2, but the sheet-metal must be sufficiently thick and rigid.

As appears from my application Serial Number 442,430 loudspeakers have already been provided with a resonance body arranged similar to a baffle board and serving also for the amplification of the air oscillations, chiefly those of the lower frequencies, which is due to the unequal propagation of the air oscillations of different frequencies. In this way the resonance body is not affected by the oscillations that spread straightway in the direction of the diaphragm axis, whereas the more or less deflected air oscillations of the lower frequencies push upon the resonance body and cause it to take part in the oscillations.

In order to provide that said presupposition—viz. the resonance body taking part in the oscillations only at the lower frequencies—be well fulfilled, care must be taken that also the air contained in the interior of the box is not directly influenced or affected by the diaphragm oscillations. For this reason the wall 4 which surrounds the diaphragm 1 must be appropriately thick so that the interior of the box is separated from the diaphragm in a soundproof manner. This wall which surrounds the diaphragm may be, what is suited to the purpose in view, so designed that it can serve at the same time as a frame which connects the diaphragm with the electromagnet 9, as is the case in the example shown. That part of the thus formed frame which lies next to the electromagnet is provided with apertures 10 in known manner.

In order to enable the resonance body to take part unimpededly in the oscillations, its aperture is made a little larger than the wall 4 that passes through it.

In Fig. 2 there are indicated by arrows also such air oscillations that arise during the reproduction of a lower tone and during the forward movement of the diaphragm. It is easily to be seen that the rigid wall 3-3^a prevents the direct equalization of the air pressures produced by the two surfaces of the diaphragm, as does the baffle plate of an ordinary loudspeaker. The oscillation phenomena at the righthand side are, thus, the same as in a loudspeaker with an ordinary baffle plate. At the left side, however, the deflected air oscillations meet the oscillable resonance board, which is set by the consecutive pushes and the resonance effect, in oscillation, and these oscillations are radiated forwardly from the resonance board, like from a diaphragm of very large dimensions, by far more energetically than the small conical diaphragm is able to do. The low-frequency air oscillations produced by this latter diaphragm serve, therefore, chiefly to cause oscillations of an essentially larger diaphragm—the resonance board—that is more capable to drive those oscillations in forward direction.

The action of the diaphragm 1 during the

reproduction of lower ranges of sounds can, thus, be compared with that of a string of an ordinary stringed instrument in which the air oscillations produced by that string itself can 5 hardly be heard, and the greatest part of the oscillatory energy is utilized for causing oscillations of a larger surface.

Anyhow, this comparison is only relatively correct and is true only as regards the very low pitches, as has already been mentioned. 10 With the higher frequencies, when the air oscillations coming from the diaphragm spread more and more rectilinearly, the share of the resonance board as regards the forwardly radiated air oscillations becomes smaller, whereas 15 the share of the diaphragm increases in the same measure. In the higher pitches of sound the totality of the air oscillations is produced in the diaphragm, whereas the resonance board (apart, of course, from the oscillations caused 20 by the strings) is practically ineffective.

Figs. 1 and 2 show also diagrammatically the housing of the reception device within the box. 11 is the receiver. At the place 12, in the lower portion of the box, is the amplifier with the power supply unit arranged therein. All 25 this apparatus may be made easily accessible, as the rigid part of the box may have closable openings like any ordinary radio chest. 13 denotes protective covers which when being opened 30 serve as lateral extensions of the rigid wall.

As appears from Fig. 1, the strings are subdivided into two sets or groups in which they are located in close proximity to one another. 35 The two groups cross one another just over the centre of the diaphragm, and at this crossing point all strings are held fast by a connecting member which, as shown in the perspective representation Fig. 3, consists of two clamping 40 cheeks 14 and 15 having suitable grooves for the reception of the individual strings. I wish it, however, to be understood that I have shown this constructional form of said members 14 and 15 only by way of example; their configuration 45 may also be otherwise; they are connected with one another by a screw 18, which not only holds the strings firmly in position between the clamping cheeks, but also serves for coupling them with the driving unit. The said 50 cheeks may consist of a light material, such, for instance, as wood, hard rubber, or the like. An intermediate layer of paste-board 19 or the like facilitates the convenient clamping fast of the strings in the grooves mentioned.

55 The just described manner of connecting the strings with one another by means of connecting members of low weight is an important feature; another feature entailing an important advantage is this that every string or, more precisely, every pair of strings, is tensioned completely independent from all other strings or pairs of strings, and can, therefore, also be tuned perfectly independent. The strings are clamped fast between the clamping cheeks only 60 after the tuning has been finished. From this moment the halves of every string operate, of course, like independent strings.

Instead of arranging the strings only in two 70 groups, as shown in the drawings, they may be subdivided into more than two groups, and stretched, as in the first described case. Also other modifications of that tensioning form are possible. The main point in all cases is this 75 that every string is attached to the resonance

body at both its ends and is connected in its middle portion with a suitably designed coupling device.

The elastically yieldable coupling member 20 mentioned in the first part of this specification 80 is arranged, as shown in Fig. 2, between the clamping device for the strings and the driving unit. The arrangement and combination of these parts appears particularly distinctly from Fig. 4, in which the parts concerned are drawn 85 to an enlarged scale. The diaphragm 1 is connected in the usual manner with the oscillatory coil 21. A transverse ledge 22 consisting, for instance, of wood connects said coil with a metallic pin 23, the front end of which is enlarged so as to form a sort of head. The front end of this pin and the rear end of a similarly shaped pin 24 are connected with one another by means of a coupling element 20 consisting of rubber and having for instance cylindrical 90 shape; the ends of the two pins fit closely into said element 20. The front end of the pin 24 is connected with the coupling cheeks 14 and 15 of the strings. The softer and more elastic the material is, of which the coupling element 100 20 consists, and the thicker the layer 27 is that is located between the head-like enlargements of the pins, the feebler will be the oscillations of the strings. By choosing the element 20 appropriately the possibility is afforded to reduce the transmission of the oscillations to the 105 strings to the desired degree.

I wish it to be understood also as regards the arrangement and combination of parts shown in Fig. 4 that I have merely shown a constructional 110 form by way of example. Many modifications of this elastically yielding coupling device are possible without constituting departures of the respective part of the invention.

Also the construction of the resonance body as 115 illustrated in Figs. 1 and 2, in which the resonance wall surrounds the rim of the diaphragm on all sides, is merely an example which is of particular value in those cases in which comparatively small diaphragms co-operate with an electrodynamic drive with loudspeakers of simpler 120 design where a possibly compact construction is aimed at from reasons of low price; a smaller resonance board arranged only laterally from the diaphragm may be provided.

A constructional form of this kind is shown 125 in Fig. 5. The principles embodied therein are completely the same as in the example shown in the other Figs. 1 and 2. Also in this case only the front wall is designed as a resonance board proper, and is attached to the rigid other part of the box in a manner permitting said board to oscillate as required for the purpose in view. There is also in this constructional form provided a rigid lateral wall 26 which separates the 130 interior of the resonance chamber from the diaphragm.

I claim:

1. A loudspeaker, comprising, in combination, 140 a large-size diaphragm, a rigid baffle board surrounding the rim of said diaphragm and extending laterally from it; a resonance body arranged in front of said baffle board and constituting with it a resonance box, the side walls of said box being attached in part to said baffle board and in 145 part to said resonance board, and a driving unit adapted to cause said diaphragm to oscillate, substantially as set forth.

2. A loudspeaker, comprising, in combination, 150 a large-sized diaphragm, a baffle-board surrounding

the rim of said diaphragm and extending laterally from it; a similarly shaped and similarly arranged resonance board constituting with said baffle board a resonance box, the side walls of 5 said box being attached in part to said baffle board and in part to said resonance board; a rigid wall surrounding the rim of said diaphragm and separating it from the interior of said resonance box, and a driving unit adapted 10 to cause said diaphragm to oscillate, substantially as set forth.

3. A loudspeaker, comprising, in combination, a large-sized diaphragm, a baffle-board surrounding the rim of said diaphragm and extending 15 laterally from it; a similarly shaped and similarly arranged resonance board constituting with said baffle board a resonance box; a rigid extension attached to the part of said baffle board next to said diaphragm, said extension reaching 20 closely to said resonance board; a rigid wall surrounding the rim of said diaphragm and separating it from the interior of said resonance box; and a driving unit adapted to cause said diaphragm to oscillate, substantially as set 25 forth.

4. A loudspeaker, comprising, in combination, a large-sized diaphragm, a baffle-board surrounding the rim of said diaphragm and extending laterally from it; a similarly shaped and 30 similarly arranged resonance board constituting with said baffle board a resonance box; a rigid extension attached to said baffle board, said extension consisting of metal; a rigid wall surrounding the rim of said diaphragm and separating 35 it from the interior of said resonance box; and a driving unit adapted to cause said diaphragm to oscillate, substantially as set forth.

5. A loudspeaker, comprising, in combination, a large-sized diaphragm, a driving unit coupled 40 with said diaphragm; a resonance box surrounding the rim of said diaphragm and extending laterally from it similarly to a baffle plate; and a rigid wall also surrounding the rim of said diaphragm and separating it from the interior of 45 said resonance box, said rigid wall being connected with said driving unit and being at the same time adapted to serve as a supporting frame uniting the diaphragm with the driving unit, substantially as set forth.

50 6. A loudspeaker, comprising, in combination, a large-sized diaphragm, a rigid baffle board surrounding the rim of said diaphragm and extend-

ing laterally from it; a resonance board arranged in front of said baffle board and constituting with it a resonance box; side walls attached in part to said baffle board and in part to said resonance board; a plurality of strings stretched over said resonance board; and a driving unit adapted to cause said diaphragm, as well as said strings, to oscillate, substantially as set forth. 80

7. A loudspeaker, comprising, in combination, a large-sized diaphragm; a driving unit coupled with said diaphragm; a resonance body; a plurality of strings stretched over said resonance body and being attached with both ends to it; and means for coupling the middle portions of said strings with the moving part of said driving unit, substantially as set forth. 85

8. A loudspeaker, comprising, in combination, a large-sized diaphragm; a driving unit coupled with said diaphragm; a resonance body; a plurality of strings stretched over said resonance body and being each attached to it at both ends, said strings forming groups in which they are arranged closely side by side, and said groups of strings crossing one another over the 95 centre of said diaphragm; members holding said groups together at the place of crossing, and a screw connecting said members with one another and coupling them with the moving part of said driving unit, substantially as set forth. 100

9. A loudspeaker, comprising, in combination, a large-sized diaphragm; a driving unit coupled with said diaphragm; a resonance body; a plurality of strings stretched over said resonance body; a member connected with said strings, and 110 a semielastic coupling element arranged between said member and the moving part of said driving unit and being connected with both of them, substantially as set forth.

10. A loudspeaker, comprising, in combination, a large-sized diaphragm; a driving unit coupled with said diaphragm, a resonance body, a plurality of strings stretched over said resonance body, a member connected with said strings, a rod connected at one end with said member, a similar rod connected with the moving part of said driving unit, and a coupling element consisting of india rubber of a suitable hardness, into the ends of which the free ends of said rods are tightly inserted without touching one another, substantially as set forth. 115 120 125
